US00D621368S

(12) **United States Design Patent**
Lee et al.

(10) **Patent No.:** US D621,368 S
(45) **Date of Patent:** ** Aug. 10, 2010

(54) **FUSE TERMINAL**

(75) Inventors: **Chul-Sub Lee**, Daegu (KR); **Sang-Hee Lee**, Kyungsangbuk-Do (KR)

(73) Assignee: **Tyco Electronics AMP Korea Ltd.**, Kyungsangbuk-Do (KR)

(**) Term: **14 Years**

(21) Appl. No.: **29/350,593**

(22) Filed: **Nov. 19, 2009**

(30) **Foreign Application Priority Data**

May 19, 2009 (KR) 30-2009-0021444

(51) **LOC (9) Cl.** 13-03

(52) **U.S. Cl.** **D13/154; D13/178**

(58) **Field of Classification Search** D13/133, D13/146, 147, 154, 161, 173, 178, 199; 439/732, 439/844, 851, 852, 865-867, 872, 877, 884

See application file for complete search history.
